UNITED STATES PATENT OFFICE.

FREDRIK LJUNGSTRÖM, OF BREVIK, LIDINGÖN, SWEDEN.

AXIAL-FLOW TURBINE.

1,341,273.

Specification of Letters Patent.

Patented May 25, 1920.

Application filed April 10, 1919. Serial No. 289,055.

To all whom it may concern:

Be it known that I, FREDRIK LJUNGSTRÖM, subject of the King of Sweden, residing at Brevik, Lidingön, Sweden, have invented 5 certain new and useful Improvement in Axial-Flow Turbines, of which the following is a specification.

In axial flow turbines, the discharge port of the turbine has been generally disposed 10 axially outside of the turbine, the result of this being a considerable extension of the turbine on account of the very large dimensions of the discharge conduits mostly used.

The present invention relates to an arrangement which allows of a shortening of 15 the turbine by locating the discharge port of it radially outside of the parts of the turbine working at a higher pressure, *i. e.* outside of the fixed casing carrying the 20 guide blades and constituting the inner wall of the discharge port.

The invention, furthermore, consists therein, that one (or a few) of the last buckets of 25 the turbine is subdivided radially in two sections in such manner that the steam is first caused to flow, through the inner and then in the opposite direction through the outer section, the same at last escaping from this outer section to the discharge port located 30 by the side thereof and inclosing the said casing.

An embodiment of the invention is shown by way of example in the accompanying drawing.

35 Figure 1 is a vertical longitudinal sectional view of the improved turbine, and,

Fig. 2 is an enlarged sectional detail of a portion thereof.

The live steam enters the turbine through 40 the opening 1 connected with the steam supply pipe, and flows through the passage 3 between the blades in the direction of the arrow 2. In this case only the last bucket 9 is extended with a bucket 4 located radially in a section 10 of the passage 3 outside

of the bucket 9, the said passage turning at 5 and leading the steam into the final outlet or discharge port 6. This outlet is in the present case located outside of the fixed casing 7 inclosing the parts of the turbine 50 working with a higher pressure. 11 denotes the rotating blade-carrying drum which is attached to the turbine shaft 14 the same as the turbine disks 12 and 13.

To prevent leakage of steam from the passage 3 directly into the discharge port 6, the intermediate space between the rotating and the fixed parts is provided with a suitable packing.

As will be seen from the drawing, the 60 steam passage between the inner and outer sections of the last buckets is formed so that the steam upon passing through the inner sections is compelled to turn so as to flow through the outer sections in the opposite 65 direction, the buckets of the outer section being radially longer than the buckets of the inner section.

What I claim as new and desire to secure by Letters Patent of the United States is: 70

An axial turbine wherein the last rotating blade section comprises two radially arranged concentric rings of blades an inner and outer so arranged that the steam first passes through the inner ring, a bent passage 75 into which the steam passes after leaving the first ring of blades and by which the steam is caused to flow in the opposite direction through the other ring, a discharge chamber into which the steam passes axially after leaving the last mentioned ring, and a housing within the chamber and surrounding the remaining blades.

In testimony whereof I affix my signature in presence of two witnesses.

FREDRIK LJUNGSTRÖM.
